United States Patent Office

Des. 183,838
Patented Nov. 4, 1958

183,838

STADIUM SEAT UNIT

Alfred C. Hoven and Walter E. Nordmark, Grand Rapids, Mich., assignors to American Seating Company, Grand Rapids, Mich., a corporation of New Jersey

Application December 9, 1957, Serial No. 48,829

Term of patent 14 years

(Cl. D15—8)

Fig. 1

Figure 1 is a front perspective view of a stadium seat unit showing our new design; and Figure 2 is a rear perspective view of the same.

We claim:

The ornamental design for a stadium seat unit, substantially as shown.
